UNITED STATES PATENT OFFICE

MILDRED C. KNAPP, OF CHICAGO, ILLINOIS

DESIGN FOR A CANDY DOLL

Application filed February 10, 1930. Serial No. 34,467. Term of patent 3½ years.

To all whom it may concern:

Be it known that I, MILDRED C. KNAPP, a citizen of the United States, and a resident of Chicago, in the county of Cook and State of Illinois, have invented a new, original, and ornamental Design for Candy Doll, of which the following is a specification, reference being had to the accompanying drawing, forming part thereof.

I claim:

The ornamental design for a candy doll, as shown.

Signed at Chicago in the county of Cook and State of Illinois this 5th day of February, A. D. 1930.
